(57) **CLAIM**

We claim the ornamental design for a tube, as shown and described.

DESCRIPTION

FIG. 1 is a top front left perspective view of a tube in accordance with my design;

FIG. 2 is a front right perspective view of a tube in accordance with my new design;

FIG. 3 is a bottom front right perspective view of a tube in accordance with my new design;

FIG. 4 is a top left perspective view of an assemblage of six tubes in accordance with FIG. 1; and,

FIG. 5 is a top plan view of a resilient support formed from a multiplicity of tubes in accordance with FIG. 1.

The broken lines in the drawings depict environmental subject matter only and form no part of the claimed design.
